FOLDABLE BABY CAR

Clarence V. Johnson, Yates Center, Kans.

Application March 5, 1946, Serial No. 652,010

11 Claims. (Cl. 155—22)

1

The invention aims to provide a rather simple and inexpensive baby car, walker or the like, which may be compactly folded when not in use, may be conveniently carried from place to place, and may be easily conditioned for use whenever desired, the invention being, therefore, particularly advantageous when traveling by automobile or otherwise.

Another aim is to provide a construction which is readily useable as a nursery chair and is thus well adapted for the use of the infants of tourists.

Figure 1 of the accompanying drawings is a side elevation, partly broken away and in section.

Figure 2 is a top plan view, partly broken away.

Figure 3 is a front elevation.

Figure 4 is a rear elevation.

Figure 5 is a vertical longitudinal sectional view on line 5—5 of Fig. 2.

Figure 6 is a disassembled perspective view showing the front construction.

Figure 7 is a detail transverse section on line 7—7 of Fig. 5.

Figure 8 is a front elevation in folded condition.

Figure 9 is a fragmentary side elevation showing a slight modification.

The drawings above briefly described may be considered as disclosing the preferred construction and while that construction will be rather specifically explained, it is to be understood that variations may be made within the scope of the invention as claimed. The construction illustrated may be formed, to a large extent, from wood but obviously the invention is not restricted to any particular material or materials.

A vertical back 10 is provided, supported by an appropriate axle 11 having wheels 12, the lower portion of said back being formed with an opening 13, providing it with legs 14.

Two foldable sides 15 extend forwardly from the back 10 and are so constructed and mounted as to be foldable in front of said back, as seen in Fig. 8. Each side 15, in the present disclosure, is composed of a rear section 16, an intermediate section 17, and a front section 18. The rear section 16 is secured at 19 to the back 10; the rear end of the section 17 is hinged at 20, on a vertical axis, to the section 16, and the rear end of the front section 18 is hinged at 21, on a vertical axis, to the front end of the section 17. The hinge lines of the two sides 15 are so relatively positioned that the folding of one side will not interfere with folding of the other side, as will be clear from Figs. 2 and 8.

2

Two arms 22 are pivoted at 23 to a transverse cleat 24 secured to the rear side of the back 10, near its upper end, the pivots being such that said arms 22 may be swung upwardly, rearwardly and downwardly to occupy a position behind the back 10 when the car is folded, as seen in Fig. 8. The lower edges of the two arms 22 are formed with longitudinal channels 25 which receive the upper edges of the side sections 16, 17 and 18 when the two sides 15 are in operative position, thus holding said sections in alignment with each other. The front ends of the arms 22 carry an appropriate tray 26.

The front side sections 18 have forwardly declined legs 27 which are releasably connected by a transverse member 28 preferably shaped to constitute a bumper. In the present disclosure, this member 28 is formed with rearwardly opening notches 29 removably receiving the lower ends of the legs 27, said legs being provided with relatively long cleats 30 lying upon the upper side of said member 28, and with other cleats 31 abutting the lower side of said member, the cleats 30 being at the outer sides of the legs 27 and the cleats 31 at the inner sides thereof. These cleats 31 are formed with openings 32 to engage bolts or other suitable fasteners 33 on the lower side of member 28 to detachably connect this member with the legs 27. When these fasteners 33 are released and the member 28 is detached from the legs 27 (see Fig. 6), the sides 15 may be folded as seen in Fig. 8, it being of course necessary to first swing the arms 22 to released position.

The rear portion of the transverse member 28, between the notches 29, is formed with a shallow recess 34 and with a ledge 35 forming the bottom of said recess, the latter being open both upwardly and rearwardly. This ledge removably supports the front end of a foot platform 36, the rear end of which extends through the opening 13 of the back 10 and rests upon the portion 37 of said back, under said opening 13. The platform 36 may be removably secured in place in any suitable way, and hooks 38, pivoted to the legs 14, are shown for this purpose, said hooks being receivable in sockets 39 in the edges of said platform. The front end of the platform 36 is held down in the recess 34 by means of cleats 40 secured to the legs 27. The shoulders formed by these cleats and the above described cleats 30 and 31, effectively stabilize the transverse front member 28 and add rigidity to the entire front structure. This front structure is provided with appropriate caster wheels 41 which may either be mounted on the transverse mem-

ber 28 as seen in most views, or may be mounted on the lower ends of the legs 27 as illustrated in Fig. 9.

A seat 42 is hinged at 43 to the back 10, between the rear portions of the sides 15, for upward swinging when the car is to be folded. This seat is preferably formed with an opening 44 having a hinged cover 45. The front edge of the seat 42 has a relatively narrow forwardly projecting portion 46 terminating at its front end in a hand grip 47. The distance from the back 10 to the hand grip 47 is considerably greater than the distance from the seat hinges 43 to the upper end of the back 10. Thus, when the seat 42 is upwardly folded as seen in Fig. 8, the hand grip 47 will be conveniently accessible for carrying the folded structure.

The above described portion 46 of the seat 42 is provided with a foldable leg 48 at its front end, the lower portion of which extends through an opening 49 in the front end of the platform 36 and is seated in an upwardly open socket 50 formed in the ledge 35. A hook or the like 51 releasably connects the leg 48 with the platform 36 and thus the elements 28, 36, 48, 47, 46 and 42 are normally held in operative relation with each other.

When the device is to be used as a baby walker, the platform 36 is removed and the lower end of post 48 is seated in the socket 50 where it will be held by gravity and the weight of the child on the seat 42, or if desired a hook and eye or similar fastening may be used for holding the post in socket 50.

An appropriate foldable handle 52 is provided, detachably connected at 53 with the lower ends of the legs 14, and at 54 I have shown a brace for connecting said foldable handle 52 with the cleat 24. As the present invention is not concerned with the specific construction of the handle, no more detailed explanation will be required.

When the car is to be folded for carrying, the arms 22 are swung over behind the back 10 as seen in Fig. 8, the hook 51 is released and the seat 42 swung upwardly so that the hand grip 47 is readily accessible, the front member 28 is disconnected from the legs 27, the platform 36 is removed, and the two sides 15 are then folded into the compact relation shown in Fig. 8, in front of the upwardly folded seat 42. The member 28, platform 36, and the folded handle 52, may then be suitably placed against one side or the other of the folded structure, and the entire assemblage may be fastened together by means of a strap or the like, or the folded assemblage may be inserted into a special carrying bag, leaving the hand grip 47 projecting upwardly for use.

After carrying the device in folded condition, it may be quickly and easily set up for use and will then be a very effective article as a baby walker, a stroller, a "kiddie car," or a nursery chair.

I claim:

1. In a foldable baby car, a back, two foldable sides extending forwardly from said back and hinged thereto on vertical axes to fold in front of said back, a foldably mounted seat between said sides, and two tray-carrying arms pivoted to said back, the lower edges of said arms having means removably engaging the upper edges of said sides to prevent accidental folding thereof.

2. In a foldable baby car, a back, two foldable sides extending forwardly from said back and hinged thereto on vertical axes to fold in front of said back, means releasably connecting the front ends of said sides, and an upwardly foldable seat

hinged to the front side of said back, said seat having a narrow forwardly extending portion provided at its front end with a hand grip, the distance from said back to said hand grip being greater than the distance from said seat to the upper end of said back, whereby said hand grip will be accessible above said back when said seat is upwardly folded.

3. In a foldable baby car, a back, two foldable sides extending forwardly from said back and hinged thereto on vertical axes to fold in front of said back, a transverse member releasably connecting the lower front portions of said sides, and a removable foot platform extending from the lower portion of said back to said transverse member.

4. In a foldable baby car, a back, two foldable sides extending forwardly from said back and hinged thereto on vertical axes to fold in front of said back, a transverse member releasably connecting the lower front portions of said sides, a removable foot platform extending from said back to said transverse member and lying upon a portion of the latter, said platform having an opening through its front end and said transverse member being formed with an upwardly open socket under said opening, an upwardly foldable seat having a narrow forwardly extending portion, and a foldable leg connected with said narrow forwardly extending portion of said seat, the lower end of said leg extending through said opening and into said socket.

5. In a foldable baby car, a back, two sides extending forwardly from said back, each of said sides being composed of sections abutting each other on vertical lines, and means hingedly connecting said sections with each other; means connecting the rearmost of said sections to said back; and releasable means for normally holding said sections to said sides in alinement with each other, said sides being foldable in front of said back when said means are released.

6. In a foldable baby car, a back; two sides extending forwardly from said back, each of said sides being composed of sections abutting each other on vertical lines, and means hingedly connecting said sections with each other; means connecting the rearmost of said sections to said back; and two tray-carrying arms pivoted to said back and having channels in their lower edges normally receiving the upper edges of said sides to hold said sections of said sides in alinement, said sides being foldable in front of said back when said arms are swung to released position.

7. In a foldable baby car, a back, a seat hinged to said back to fold upwardly when not in use, said seat having a narrow forwardly extending portion provided at its front end with a hand grip, and releasable means for holding said seat in operative position, the distance from said back to said hand grip being greater than the distance from said seat to the upper end of said back, whereby said hand grip will be accessible when said seat is upwardly folded.

8. In a foldable baby car, a back, foldable sides hinged to said back and having legs at their front ends, a transverse member extending between the lower ends of said legs and having notches in which said lower ends of said legs are removably seated, said legs having shoulders abutting the upper and lower sides of said transverse member, and releasable means normally holding said legs in said notches.

9. A structure as specified in claim 8; together with a removable foot platform resting at its

front end upon said transverse member between said legs, said legs having shoulders abutting the upper side of said platform.

10. In a foldable baby car having a front transverse member and an upwardly foldable seat; a removable platform resting at its front end upon said transverse member and having an opening, and a leg projecting downwardly from said seat and having its lower end removably received in said opening.

11. A structure as specified in claim 10; said transverse member having an upwardly open socket removably receiving the lower extremity of said leg.

CLARENCE V. JOHNSON.
